UNITED STATES PATENT OFFICE.

HENRY W. BUHLER, OF BOSTON, MASSACHUSETTS.

COKE-OVEN.

1,319,840.

Specification of Letters Patent.

Patented Oct. 28, 1919.

Application filed January 18, 1917. Serial No. 142,996.

To all whom it may concern:

Be it known that I, HENRY W. BUHLER, a citizen of the United States of America, residing at Boston, county of Suffolk, State 5 of Massachusetts, have invented certain new and useful Improvements in Coke-Ovens, of which the following is a specification.

My invention relates generally to heating apparatus employing fluid forms of fuel 10 such as gas or oil, but is more specifically designed for use in coke ovens having a plurality of heating flues. These flues are usually formed in the walls between the retorts of the coke oven and arranged vertically. As heretofore built these flues have been somewhat inaccessible for cleaning or 15 observation and difficult of individual control.

It is most important in coking operations 20 that the retort heating system shall be flexible and responsive to control both as a whole and in its individual units, since it is necessary to produce uniformity of heating at times and individual variations of 25 heating effect at other times. It is also important that there shall be facility of inspection, cleaning, or simple repair of any one unit without shutting down the operation of the entire system. My invention accom- 30 plishes these objects and, as herein illustrated, is shown applied to a coke oven having horizontal retorts with vertical combustion flues and waste gas flues formed in pairs in the walls between the retorts, this 35 being the best form of apparatus embodying my invention at present known to me. In the drawings—

Figure 1 is a vertical section through a coke oven, the section shown in the right 40 hand half being taken on planes passing through the waste gas flues on the irregular dotted line C—D, and the section shown in the left hand half on a plane passing through the heating flues on dotted line 45 A—B, of Fig. 2.

Fig. 2 is a vertical section on planes perpendicular to those of Fig. 1, the section shown in the right hand half being taken on a plane passing through the waste gas flues 50 on a dotted line G—H, and the section shown in the left hand half on a plane passing through the heating flues on a dotted line E—F, of Fig. 1.

Fig. 3 is a horizontal section on line I—J 55 of Fig. 1.

Throughout the drawings like reference characters indicate like parts: 1, 1, represent retorts or coking chambers having side walls 2, 2, a common top wall 21, and a common base or foundation having galleries 22, 22, therein. In the side walls are a plurality of vertical combustion flues, 3, 3, and waste gas flues 4, alternating one with another and arranged in tandem, and all tributary to the common horizontal flue or collecting conduit 5, located above them. As indicated by the arrows, each combustion flue 3, discharges into conduit 5, through a slightly restricted opening or mouth 19, and each waste gas flue 4, draws gases of 70 combustion or gases in process of combustion from said conduit through an opening therefrom which may be varied in size by manipulation of damper 6, which is merely a loose tile of refractory material which is 75 confined and guided in its sliding movements by raised lips 18, 18, on the flue ends. Preferably the conduit 5, is formed in a straight line from end to end, and at one or both ends are formed observation ports or 80 peep holes 20, 20.

11, 11, are gas mains in galleries 22, 22, connected to burners, or gas nozzles 13, 13, controlled by valves 12, 12. These burners extend through vertical passageways 14, 14, 85 in the base of the oven nearly to the lower ends of combustion flues 3, 3. Air is supplied to said combustion flues from passages 15, 15, through branches 16, 16, in the oven base. 90

Waste gas flues 4, 4, discharge through collecting flues 17, 17, also formed in the oven base.

7, 7, are passageways in the top wall 21, of the oven opening out of collecting conduit 5, opposite the dampered inlets to waste flues 4, 4, and 8, 8, are removable covers for these passageways. 9, 9, are similar passageways opening out of collecting conduit 5, opposite the mouths of combustion flues 100 3, 3, and 10, 10, are removable covers for this second set of ports or openings.

In operation gas and air are discharged in proper proportions into the lower ends of flues 3, 3, where they combine and the 105 flames then pass up through the flues and through openings or flue mouths 19, 19, to collecting conduit 5, and perhaps part way down the adjacent waste gas flues 4, 4, ultimately passing out through collecting flues 110

17, to a chimney (not shown). The flue walls and walls of conduit 5, are maintained a white heat throughout if all flues are working normally. If for any reason 5 proper combustion is not taking place in any flue 3, the adjacent portion of the wall of conduit 5, will darken in color and the operator, looking through observation port 20, is immediately advised thereby of the 10 fact of trouble and of its location. The imperfect working of the offending flue can then be immediately corrected by manipulation of adjacent dampers 6, 6, or of the proper gas valve 12, or by both means. As 15 shown, the conduit 5, is of small cross section, the area of its cross section being little larger than, or approximately equal to that of the mouth 19, of each combustion flue or the undampered inlet to each waste gas flue 20 4. In other words, the areas of the discharge mouths 19, 19, of flues 3, 3, and of the intake mouths of flues 4, 4, when the latter are given their maximum area by moving dampers 6, 6, to the extreme left 25 hand positions, looking at Fig. 2, do not vary greatly, and the cross sectional area of conduit 5, is approximately the same as that of each port 19, 19. In any event the conduit capacity should be much less than 30 the aggregate capacity of all the combustion flue outlets, or of all the waste gas flue inlets. Consequently the suction of each waste gas flue is substantially local in its effect on the contents of conduit 5, and this 35 suction is transmitted to only the adjacent combustion flues, *i. e.* it takes burning gases from only the two adjacent combustion flues. Thus each waste gas flue acts only on such adjacent combustion flues unless its suction is varied widely in effect from that of other waste gas flues. If the darkening color of the collecting conduit walls adjacent to a given combustion flue shows the operator that such flue is not 40 doing its full duty the reason probably is that the draft on it is below requirements. Accordingly the operator will remove cover 8, over one or both the adjacent waste gas flues, 4, 4, reach in with a proper tool and 45 move their dampers 6, 6, so as to increase the openings to each flue, thereby accelerating the draft and correcting the trouble. Also, if too great heat is being developed in any zone of a retort 1, a partial closing of 50 dampers 6, 6, in flues adjacent to that zone 55 will reduce combustion, and vice versa.

Passageways 14, and 9, also afford access to flues 3, 3, by any proper cleaning tools. This would usually be done through passageway 9, alone, but, if necessary, burner 13, could be removed and passageway 14, used as an avenue of discharge for clinker or other debris collected in the flue 3, such clinker being first broken up by tools inserted through the upper passage 9. In

the same way passageways 7, 7, may be used for inserting tools for cleaning flues 4, 4, as well as for manipulating dampers 6, 6.

The advantages of my invention comprise the above described flexible, individual control of any flue or group of flues without interfering with the mass control of the whole system (as by variations in total chimney draft), the perfect accessibility of all flues and passages and the perfect ease of complete inspection and observation of all portions of the heating apparatus while in use. 75

I wish it understood that various changes can be made in the details of construction shown and described without departing 80 from the substance of my invention so long as the general principles of operation and coaction of parts herein set forth are preserved.

Having described my invention, I claim: 85

1. In a heating apparatus the combination, with a plurality of combustion flues and waste gas flues arranged in series alternately to form a plurality of heating units each provided with air and fuel supplying 90 and waste gas removing means, of a conduit extending along the ends of all said flues and forming the sole means of communication between the members of each unit, and individual means for controlling such communication. 95

2. In a heating apparatus the combination, with a plurality of combustion flues and waste gas flues arranged in series alternately to form a plurality of heating units 100 each provided with air and fuel supplying and waste gas removing means, of a conduit extending along the ends of all said flues and forming the sole means of communication between the members of each unit and individual means for controlling such communication, said individual means comprising a movable damper placed across the port by which each waste gas flue communicates with the collecting conduit. 105

3. In a heating apparatus the combination, with a plurality of combustion flues and waste gas flues arranged in series alternately to form a plurality of heating units each provided with air and fuel supplying 115 and waste gas removing means, of a conduit extending along the ends of all said flues and forming the sole means of communication between the members of each unit, and individual means for controlling such communication, said collecting conduit being provided with a port through which the condition of its interior adjacent each combustion flue can be observed. 120

4. In a heating apparatus the combination, with a plurality of combustion flues and waste gas flues arranged in series alternately to form pluralities of heating couples 125 each provided with air and fuel supplying and waste gas removing means, of a conduit 130

extending along the ends of all said flues and forming the sole means of communication between the members of each unit, and individual means for controlling such communication, said collecting conduit being provided with an opening in its wall opposite the end of each flue and in line with the axis thereof.

5. In a heating apparatus the combination, with a plurality of combustion flues and waste gas flues arranged in series alternately to form a plurality of heating units each provided with air and fuel supplying and waste gas removing means, of a conduit 10 extending along the ends of all said flues and forming the sole means of communication between the members of each unit and individual means for controlling such communication, said individual means comprising a 15 movable damper placed across the port by which each waste gas flue communicates with the collecting conduit, said combustion flue ports being of substantially uniform area of opening and said conduit having a cross sectional area approximating thereto.

20

25

nately to form a plurality of heating units each provided with air and fuel supplying 30 and waste gas removing means, of a conduit extending along the ends of all said flues and forming the sole means of communication between the members of each unit, and individual means for controlling such communication, said individual means comprising a movable damper placed across the port by which each waste gas flue communicates with the collecting conduit, said combustion flue ports being of substantially uniform 35 area of opening and said conduit having a cross sectional area approximating thereto.

7. In a heating apparatus the combination, with a plurality of combustion flues and waste gas flues arranged in series alternately to form a plurality of heating units, of a single collecting conduit extending along the ends of all said flues and communicating therewith, the maximum individual areas of all the communicating openings 45 being substantially uniform each with the others, and the cross sectional area of the collecting conduit being approximately equal thereto.

HENRY W. BUHLER.
